United States Patent Office

Des. 183,231
Patented July 15, 1958

183,231

FIRESET STAND

John B. Turner, Norwich, N. Y., assignor to Bennett-Ireland, Inc., Norwich, N. Y., a corporation of New York

Application October 4, 1956, Serial No. 43,230

Term of patent 14 years

(Cl. D81—24)

Fig. 1 is a perspective view of a fireset stand showing my new design;

Fig. 2 is a front elevational view;

Fig. 3 is a side elevational view; and

Fig. 4 is a top plan view.

I claim:

The ornamental design for a fireset stand, as shown.
